ANTONIO FERRER DALMAU, OF BARCELONA, SPAIN

AUTOMATIC BLOCK SYSTEM

Application filed November 19, 1929, Serial No. 408,339; and in Spain November 20, 1928.

Under the name of block system are grouped, in railway technology, all the automatic safety devices in railway service.

The fundamental characteristic of the block forming the subject of this invention is that of producing the true blocking of the sectors when they are occupied by a train, thus preventing any other train entering the same sector, and it differs from other known safety devices in that by its normal operation, which is completely automatic and consequently requires no human intervention, it corrects all errors which may be made in setting the signals and points and mistakes in reading the signals by the engineers or drivers of the train, this result being obtained without the necessity of electrifying the line in any way, and merely at the cost of a small generator installed upon the locomotive or other unit of the train.

The installation of this block system forming the subject of the present invention requires the whole of the network of the railway to be divided up into blocking sectors or divisions of varying length, which may cover the whole of the track between two stations and all and each of the tracks and points and sidings of the stations are considered as sectors or parts of a sector in an absolute manner, since there should be no part of the track which does not form part of a sector.

Each sector is formed by a circuit with one or more relays which, when it operates, connects to earth one of the terminals of other circuits which terminate at their other ends in fixed contact pieces suspended from posts near the track.

The block system according to the invention is illustrated diagrammatically in the accompanying drawings.

Fig. 1 is a diagrammatic view of a section or block of track showing the invention applied thereto.

Fig. 2 is a diagrammatic presentation of the car-carried apparatus.

Fig. 3 is a diagrammatic view similar to Fig. 1 showing the manner of overlapping the electrical connections at two contiguous sections or blocks of the track.

Fig. 4 is a diagrammatic view of the track apparatus of one block showing also a more detailed view of the train carried apparatus.

Figs. 5, 6 and 7 are views similar to Fig. 1 showing modifications of the invention.

Figs. 8 and 9 are diagrammatic views of further modifications of the track apparatus.

Referring to the drawings in detail, the numeral 1 indicates a section or "block" of the track in connection with which the invention is used. A conductor 9 is extended throughout the length of the block 1 and is suitably insulated from the earth, and the opposite ends thereof are connected with the terminals of the coils 5a of relays indicated at 5 Fig. 4. The opposite terminals of the coils 5a are grounded as at 8 to one or both of the track rails of the block or directly in the earth, as desired. In operation, the relays 5 are adapted to alternately connect stationary contact elements 2 and 4 with the ground connection 8 incident to successive actuations of the relays, in a manner which will be hereinafter more fully described. Branch conductors are connected with the main conductor 9 and with the elements 3 associated with the relays 5. The contact element 3 at each end of the block 1 is located in a position intermediate the elements 2 and 4 with reference to the direction of movement of a train, while the contact element 3 is located at a different elevation from the elements 2 and 4 so that the first and second contact elements are separately engageable by two different train carried contact shoes.

From the foregoing it is evident that the coils 5a are permanently grounded, and it is merely necessary to connect them with a grounded source of energy through the contact elements 3 in order to energize the coils.

In Fig. 4 a form of relay 5 suitable for use in connection with the apparatus is illustrated and in which the armature of the coil 5 is connected with a movable pawl *a* coacting with a ratchet wheel *b* carried by a drum *c*. The drum is formed of insulating material and is provided with a plurality of equidistant inserts of conducting material *d*. Pairs of brushes 2a and 4a are arranged to bear on the surface of the drum *c*, and in

the position shown in Fig. 4 the brushes 4a contact with a conducting part of the drum, and therefore the contact element 4 is electrically connected with the ground connection 8 through the conductors 4b and the brushes 4a. In this position the brushes 2a bear on the insulating material and connection of the contact element 2 with the ground is interrupted. In each actuation of the relay 5 the connection of the respective contact elements 2 and 4 with the ground 8 is made and broken.

The train carried part of the apparatus is shown in Fig. 2 and consists of contact shoes 12 and 13, the shoe 13 being engageable with the contact elements 3 and the shoe 12 being engageable with the elements 2 and 4. The shoes 12 and 13, as will be understood, are suitably insulated from the locomotive or car to which they are applied, while the energy for the operation of the signal apparatus is supplied by a generator, battery or other source of electromotive force 11, one of the poles of which is grounded on the car as at 11a. Conductors 15 and 17 are connected with the opposite pole of the source 11, the conductor 15 being connected directly with the contact shoe 13 and the conductor 17 being connected with the contact shoe 12 and connected in series with a relay 18 whereby incident to closure of the circuit of which the conductor 17 forms part the indicating and train control mechanism of the train carried apparatus is brought into operation. As suggested in Fig. 4, the armature controlled by the relay 18 may be connected with the mechanism controlling the brakes and steam supply valve as well as with suitable audible signals.

Under normal conditions, when the block 1 is unoccupied by a train, the two outer contact elements 2 are disconnected from the ground connections 8 by the relays 5 so that the first train entering the block will freely pass the contact element 2, but upon engagement of its shoe 13 with the contact element 3, the relay 5 is energized and actuating the drum 6 connection between the contact elements 4 and the ground 8 is interrupted and at the same moment the outer contact elements 2 are connected with the ground. The contact elements 2 remain connected with the ground throughout the passage of the train through the block, and on leaving the latter the shoe engaging the contact element 3 again actuates the relays 5 and restores the block apparatus to its former condition, i. e. reestablishes connection between the elements 4 and the ground 8 and disconnects the latter from the element 2. However, should a second train enter the block 1 following the entry of the first train in either direction, the outer contact element 2 being directly connected with the ground would instantly close the circuit including the shoe 12, the con-

ductor 17 and relay 18, and thereby effect operation of the train carried control and signal apparatus.

As suggested in Fig. 3, the conductors of the track apparatus which terminate in the sets of contact elements 2, 3 and 4 overlap. In Fig. 3, however, the innermost contact elements 4 of each block as shown in Fig. 1 have been omitted, and a train entering the block and engaging the element 3 effects operation of the relays 5 so as to form a connection between the elements 2 and the ground connection 8. Thus, the entry of a second train into the block is prevented, and the first train on leaving the block brings the relays 5 to initial position incident to engagement of the train shoe 13 with the element 3. The overlapping of the blocks as shown in Fig. 3 extends the protection of the system over the entire length of the track, avoiding interruption as between the ends of spaced contiguous blocks.

Fig. 5 illustrates a modification of the invention in which a conductor 10 is provided connecting the ground 8 at one relay with the ground connection of the relay at the opposite end of the same block while in Fig. 6 an arrangement is shown wherein a single relay is provided at any point in the length of the block and is under the control of the sets of contact elements 2 and 3 at the terminals thereof.

Fig. 7 discloses an arrangement which is adapted for use at a point where the track is subjected to heavy traffic. In this case the first train will act upon the terminal relays 5 and 105 at the ends of the block to prevent entry of a second train, but when the first train has passed over a section of the track it will open the point of entry, that is restore the relay 5 to normal condition by actuation of the relay at 95 in order to permit the next following train to enter, the latter restoring the relay 5 to its former position without actuation of the relay 105 and thereby preventing entry of a third train into the block until the passage of the first train past the relay 105.

Referring to the modification of the invention shown in Fig. 8, this arrangement is primarily intended to provide for the more uniform distribution of current to the relays of a signal block upon entry of a train at one end thereof. According to this arrangement secondary relays 6 and 106 are provided in association with the relays 5 and 105, respectively.

Each of the relays 6 and 106 includes an auxiliary coil 27 and 127 respectively, the latter being interposed between the contact elements 3 and 103 and the conductor 9. Normally closed circuit controlling devices 27a and 127a are interposed between the opposite terminals of the coils of the relays 5 and 105.

and 105 and the ground connections 8 and 108 and resistances 28 and 128 are shunted across the points. Resistance elements 28 and 128 having a value approximately corresponding to the resistance offered by the conductor 9 are selected, and upon entry of a train into the block 1 the coil 27 is energized simultaneously with the coil of the relay 5, and the circuit controller 27a is caused to open the connection between the relay coil 5 and the ground connection 8 and cause the current to pass through the resistance 28 at that end of the block. Thus, two paths of equal resistance are offered for the passage of the current, one through the coil of the relay 5 and over the resistance element 28 and the other over the conductor 9 and through the coil of the relay 105 and closed circuit controller 127a.

The arrangements according to the invention may be applied in the same way to an intermediate block as to a terminal block or station and they are shown by way of example as applied to a terminal station in Figure 9.

In this figure, 9 and 10 are the two usual wires of the block adjacent the terminal or station which, as explained above, comprises the contact elements 112, 113, 114 and the ground connection 108. These contact elements are supplemented by another contact 123 which forms the station entry contact.

In combination with these contacts is a resistance 36 which is equivalent to the resistance controlled at 6 and 106 previously described, and a relay 35 which is the equivalent of the relays 5 and 105 with the sole difference that in addition to the usual switch 37 it comprises a supplementary contact 38 which is adapted to light the lamp of the indicator board 60.

In the station shown, it is assumed that the line of track 1 is divided by means of two track switches 71, 72 into three branch lines 31, 32, 33, and in combination with these branch lines the station entry contacts are connected by means of conductors 41, 42 and 43 with three mechanisms. Each one of these mechanisms comprises a relay 46, 56 and 66, respectively each of which is actuated by currents sent from the switches 81, 82 coupled with the track switch mechanisms 71, 72. Moreover, with these relays are combined other relays 45, 55 and 65 similar to the relays 35 and each comprising a switch 47, 57 and 67 similar to the switches of the relays 5 of the individual blocks, and in addition switches 48, 58, 68 for the lamps of the indicator board 60.

In order to operate all these devices the station comprises a battery or local generator 34 one of the poles of which is grounded through the conductor 108. The other pole of the battery is connected by the conductor 39 with the switch 81 and one of the two

contacts of this switch 81 is connected by the conductor 64 with the switch 82, whilst the other connects with the relay 46. The two contacts of the switch 82 are connected respectively with the relays 56 and 66 so that upon moving the points by means of the track switches 71, 72 in order that a train which enters along the line 1 may be directed on to a given branch line of the station, the combination of the switches 81 and 82 is established at the same time and the relay 46, 56 or 66 is actuated which corresponds to the branch of track selected.

In Figure 9, the station has been shown in the assumed case when a train in the block 1 in advance of the station enters the station along the track 1 and the track switches are set so that this train, upon entering the station, will pass on to the branch 32. When the points are set in this position, the current from the battery 34 passes through the switch 81 and conductor 64 to the switch 82 and from the lower contact of the latter the current passes to the coil of the relay 56 and actuates this relay thus closing the two contacts of the latter, as shown in the drawings. The current then travels along the wire 10 to the conductor 108.

The indicator board 60 has a representation of the tracks of the station on a reduced scale, with a series of indicating lamps thereon. The lamp 51 indicates when the track 1 is occupied by a train which occupies the block in front of the station. The lamps 61, 62 and 63 indicate respectively when each is illuminated that the corresponding track 31, 32 or 33 is occupied and, independently of these lamps, the lamps 52, 53 and 44 and 54 indicate the position of the track switch points 71 and 72.

When the train which approaches the station has entered the adjacent block and caused it to be blocked, it has caused the relay 35 to operate, thus putting it into position shown in the drawings, and when the contact 38 closes, the lamp 51 on the board 60 becomes illuminated, thus indicating that there is a train on the section in front of the station. Then, by setting the points in the position shown in the drawings, the current from the battery 34 passes to the switch 82 along the wire 49 to the lamp 44 the circuit is closed through the ground conductors 10 and 108. Consequently the lamp 44 has become illuminated, indicating that the line 32 is the one which is connected with the line 1 for receiving the train.

When the train reaches the contact 112, the current cannot pass because the conductor 41 is not connected with earth. Upon then passing the contact 123, the current from the locomotive travels along the conductor 42 and passes through the coil of the relay 55 thus actuating this relay and changing over the position of the switch 57, contact 112 is con-

nected with the ground, and by the closure of the contact 58 the lamp 62 is illuminated, thus indicating that this line is occupied by a train.

When the train then passes the contact 113 which forms the outlet of the block, it causes the resistance 36 and the relay 35 to operate and interrupt connection between the contact 112 and the ground. Upon then passing the contact 114 the current can still not pass because 114 is not grounded.

The train then enters the line 32 and if a following train enters the station without the position of the switch points being changed when it passes the contact 112, the current 15 from the locomotive passes through the conductor 41, the switch 57, the contact of the relay 56 as far as the ground wire 10 thus causing the alarm signals of the locomotive to operate. On the other hand if, before 20 reaching this train the position of the points has been changed, the relay 56 will then change the position of interruption and in changing will close the relay 46 or 66 corresponding to the track which is connected 25 with the line 1. Consequently, the train will be able to enter the station and travel along the other line while the line 32 remains occupied.

The invention also enables the station chief 30 to lock at will any of the lines 31, 32, 33 even though no train is on them. For this purpose three switches 76, 77, 78 are provided which are actuated by hand, while switches 35 establish a communication between the conductor 41 and one of the contacts of the relays 46, 56, 66. For example, if the station chief closes the switch 77, the track 32 will be blocked when the points are set, to make it communicate with the track 1. In effect, 40 when the train reaches the contact 112, the current from the locomotive will pass along the conductor 41 and switch 77 to the relay 56 and, as the latter will hold the contacts closed by the operation of the point switches 45 81 and 82, the current will close the circuit to earth thus causing the alarm devices on the locomotive to operate.

I claim:—

1. A block system for railway networks and 50 the like comprising, at each end of a sector of track, two contacts and a relay mounted on the side of the track, and a source of electrical energy, electrically operated warning devices and contact bars on the locomotive, 55 the said contact bars and warning device being permanently connected to the said source of energy and the said bars cooperating with the said contacts so as to close circuits containing said relays when the train enters said sector, and open said circuits when the train leaves said sector, and so as to close circuits 60 containing the alarm devices when the train approaches an occupied sector the relays at both ends of the sector having one of their 65 terminals in communication with the corre-

sponding contact and the other in communication with earth, the entering connectings of both relays being connected together by a metal conductor and the two earth contacts also connected together by another metal conductor whereby the good operation of the relays is secured even though one of the earth contacts is defective. 70

2. A block system according to claim 1, the relays at both ends of the sector having one of their terminals in communication with the corresponding contact and the other in communication with earth, the entering connections of both relays being connected together by a metal conductor and the two earth contacts also connected together by another metal conductor whereby the good operation of the relays is secured even though one of the earth contacts is defective, a supplementary resistance being combined with each of the two relays at the ends of the sector, this resistance being connected automatically into the circuit of the relays when the contact directly connected to this relay operates, whereby the resistance of the conductor which 80 unites the relays at both ends of the sector is compensated and the current which passes through both relays is caused to be of equal value. 85

3. A block system according to claim 1, the relays at both ends of the sector having one of their terminals in communication with the corresponding contact and the other in communication with earth, the entering connections of both relays being connected together by a metal conductor and the two earth contacts also connected together by another metal conductor whereby the good operation of the relays is secured even though one of the earth contacts is defective, a supplementary resistance being combined with each of the two relays at the ends of the sector, this resistance being connected automatically into the circuit of the relays when the contact directly connected to this relay operates, whereby the resistance of the conductor which 90 unites the relays at both ends of the sector is compensated and the current which passes through both relays is caused to be of equal value. 95

4. A block system according to claim 1, the relays at both ends of the sector having one of their terminals in communication with the corresponding contact and the other in communication with earth, the entering connections of both relays being connected together by a metal conductor and the two earth contacts also connected automatically into the 130

circuit of the relays when the contact directly connected to this relay operates, whereby the resistance of the conductor which unites the relays at both ends of the sector is compensated and the current which passes through both relays is caused to be of equal value, there being two pairs of contact bars on the locomotive, suitably situated so that the bars of each pair touch one of the two contacts at each end of the sector, a bar of each pair being also situated symmetrically on each side of the locomotive, so that the latter can travel along the line in either direction, one of the poles of the said source of energy being in communication with earth and the other in communication with the contact bars connected between the current generator and one of the pairs of contact bars, an electromagnet on the locomotive, which, when the bar touches a contact on the track connected to earth, actuates a switch on the locomotive which operates the alarm signals and if desired the brakes of the train.

In testimony whereof I have signed my name to this specification.

ANTONIO FERRER DALMAU.
